ACOUSTICAL ROOF DECK

William Kuehne, Chicago, Ill., assignor to United States Gypsum Company, Chicago, Ill., a corporation of Illinois

Application July 25, 1932, Serial No. 624,379

7 Claims. (Cl. 108—13)

This invention relates to building constructions, and has reference more particularly to metal roof decks having sound absorbing materials assembled with the deck to form a unit. 5 In correcting acoustics in industrial buildings, schools, etc., I have found it desirable to utilize a combined metal roof deck having depending, U-shaped ribs, with a sound absorbing pad faced with a perforated metal membrane, the whole being assembled at the factory and shipped 10 to the job as a unit. In making such a unit, I prefer to have individual elongated perforated membranes having outstanding legs fitting between the legs of the roof deck, and support said 15 membranes from the legs of the roof deck by members which are inserted into apertures formed in the roof deck legs. Some difficulty has been experienced in forming the apertures in the legs of the roof deck so that all of said 20 apertures are of equal distance from the connecting web of the roof deck legs.

An object of this invention, therefore, is to provide an acoustical roof deck unit which may be conveniently shipped in an assembled condition to the job for easy and quick erection. 25

Another object of the invention is to provide a method of forming apertures in the legs of metallic roof decks so that said apertures are all of equal distance from the webs of the roof 30 deck ribs.

A further object of the invention is to provide an acoustical roof deck in which assembly of the various parts of the roof deck are conveniently made by means of elongated support members which support both the perforated membranes and the acoustical pads; also to improve building constructions and their method of manufacture in other respects hereinafter specified 35 and claimed.

40 Reference is to be had to the accompanying drawings forming a part of this specification, in which

Fig. 1 is a perspective, sectional view of a roof 45 embodying my improved construction,

Fig. 2 is a perspective view of a roof deck section,

Fig. 3 is a perspective, sectional view of a 50 perforated metal, membrane unit,

Fig. 4 is a sectional elevation through the 55 acoustical roof deck.

Fig. 5 is a longitudinal sectional elevation through telescoping acoustical roof decks,

Fig. 6 is a sectional elevation through a slight- 55 ly modified form of the acoustical roof deck at

the longitudinal junction with an adjoining roof deck,

Fig. 7 is a sectional elevation through a tool 5 for forming slots in the legs of the roof deck, and

Fig. 8 is a sectional elevation through a machine for forming slots in the legs of the roof deck.

The roof deck element forming a part of my improved construction comprises a plate 10 on which are formed preferably a plurality of outwardly extending, integral, U-shaped ribs 11. An outwardly extending, longitudinal flange 12 is formed on one edge of the plate 10 and an outwardly extending U-shaped rib or channel 13 is formed on the opposite longitudinal edge of said 15 deck plate. Beads 14 are formed in the plate 10 between the ribs, said beads extending from one end of the deck to a point short of the other end of the deck. The beads 14 serve to reduce the width of the plate section 10 adjacent one end 20 of the deck plate so that two deck plates have sufficient clearance to telescopically overlap end to end to form a roof. The roof decks also telescope along their longitudinal edges with the flange 12 of one roof deck position in the channel shaped rib 13 of the adjoining roof deck 25 (Fig. 6). Roof deck plates are supported upon suitable steel framework 10a and are preferably covered on the upper surface by a sheet of fiber board 16 serving as heat insulation, this fiber 30 board being covered with asphalt shingles 17 or other suitable weather protective coating.

Supported between legs 18 of the ribs 11, are provided elongated perforated metal membrane sections 19 which have outwardly extending flanges 20 formed along each longitudinal edge thereof. Holes 21, preferably triangular shape or any other desired shape such as round, oval, etc., are formed uniformly over the surface of the membrane 19. In order to support the membrane sections 19 between the ribs 11, I form 35 apertures 24 in the legs 18, said apertures in a given length being uniformly spaced above the bottom of the ribs 11. The apertures may be formed by a tool 26 having jaws terminating in 40 inwardly extending, opposed punches 27. During the punching operation, an elongated die 28 having longitudinal grooves 29, is inserted 45 in a rib in such a way that the punches 27 serve to force the metal of the rib legs 18 into the grooves 29 and form severed shoulders 30 in the legs 18. If desired, all of the apertures 24 may be punched simultaneously in a roof deck section 50 by means of rotary cam cutters 31 mounted upon shafts 32 which are rotatably mounted in 55

bearings 33 carried by a support plate 34. Each of the shafts 32 is provided with a spur gear 35, said spur gears meshing in series, the last gear in the series meshing with the spur gear 36 mounted upon a driven shaft 37. Dies 38 similar to dies 28 are mounted to engage within the ribs of the roof deck during the continuous movement of the roof deck after the rolling operation so the cam cutters 31 which are rotated continuously or intermittently by means of automatic controls not shown associated with the shaft 37, form the apertures 24 by a single rotation of the cam cutters 31 without stopping the movement of the roof deck.

In order to absorb the sound passing through the perforations 21 in the membrane 19, I provide a fibrous pad 40 of sound absorbing material such as mineral wool, hair felt, etc. In order to support the pads 40 in spaced relation to the membranes 19, I provide U-shaped wire hangers 41 having upstanding legs 42 which terminate in outstanding ends 43, the latter engaging in the apertures 24 to lie on top of the severed shoulders 30, the outward movement of the hanger ends 43 being limited by engagement with the offset metal pads 29a formed by the punches 27. When using pads 40 which are fairly flexible, it is preferable to provide zigzag sections 45 formed in the wire hangers 41 for the purpose of supporting abutting ends of adjoining pads 40 where the ends of the roof decks telescope to prevent said pads from sagging between hangers and contacting with the perforated membranes 19. The outstanding hanger ends 43 also pass through apertures formed in the membrane legs 20 which are positioned to register with the apertures 24. It will be noted that hangers 41 thus support both the membrane sections 19 and the fibrous pads 40 by engagement with the shoulders 30. The pads 40 are supported out of contact with the membranes 19 so that the lower surface of said membranes may be washed or cleaned from time to time as they become soiled without causing the pads 40 to become wet by the wash water.

By the use of the punch 26 and dies 28, the apertures 24 are formed at a uniform height above the bottom of ribs 11 at all times thus insuring that the bottom faces of membrane sections 19 all lie in a uniform plane slightly above the bottoms of ribs 11. Where the longitudinal lap of roof decks occurs (Fig. 6) the outstanding hanger ends 43 may be made slightly longer to allow for the thickness of the roof deck flange 13 which will lie between the flange 12 of one of the adjoining roof deck and upstanding legs 20 of one of the membrane sections 19. In Figure 6, the construction is slightly modified in that the metal is not severed adjacent shoulders 30a thus making the roof deck a water-shed immediately upon erection.

I would state in conclusion that while the illustrated example constitutes a practical embodiment of my invention, I do not wish to limit myself precisely to these details, since manifestly, the same may be considerably varied without

departing from the spirit of the invention as defined in the appended claims.

Having thus described my invention, I claim as new and desire to secure by Letters Patent:

1. In an acoustical roof deck, a metal sheet having a plurality of U-shaped stiffening ribs, the legs of said ribs being provided with apertures, perforated metal membranes having outstanding flanges fitting between said ribs and having apertures registering with the apertures of said ribs, U-shaped support members having outstanding ends passing through the registering apertures of said flanges and legs, and a sound absorbing pad supported by said members in spaced relation to said membrane. 15
2. In an acoustical roof deck unit, a perforated, elongated, metal membrane having outstanding flanges formed on the longitudinal edges thereof, U-shaped support members having outstanding ends extending through apertures formed in said flanges, and a sound absorbing pad supported by said support members to form an acoustical unit. 20
3. In an acoustical roof deck, an imperforate metal plate having integral outstanding ribs 25 pressed from said plate, a perforated metal membrane extending between said ribs in spaced parallel relation to said plate, support members extending between said ribs and having the ends of said members secured to said ribs, and an acoustical pad supported by said members in spaced, parallel relation to said membrane. 30
4. In an acoustical roof deck, a metal plate having apertured, outstanding, U-shaped ribs, a perforated metal membrane extending between said ribs in spaced, parallel relation to said plate, support members extending between said ribs and having the ends of said support members extending into the rib apertures, and a sound absorbing pad supported by said support members. 40
5. In an acoustical roof deck, a metal plate having integral apertured, outstanding U-shaped ribs pressed from said plate, U-shaped wire extending between said ribs and having outstanding ends extending into the rib apertures, and a sound absorbing pad and perforated metal membrane supported by said wires. 45
6. In an acoustical roof deck, a metal plate having apertured, outstanding ribs, a perforated metal membrane extending between said ribs, 50 wire support members having outstanding ends extending into the apertures of said ribs, zigzag bends in said wires between said ribs, and a sound absorbing pad supported by the bends of said wire support members. 55
7. In an acoustical roof deck, a metal plate having outstanding, U-shaped ribs, struck out pads formed in said ribs forming severed shoulders, support members having outstanding ends supported on said shoulders and bearing against said pads, perforated metal membrane extending between said ribs, and a sound absorbing pad supported by said support members. 60
